[57] CLAIM

The ornamental design for a case for eyeglasses, as shown.

DESCRIPTION

FIG. 1 is a front perspective view from above and one side of a case for eyeglasses showing my new design; the bottom being plain and unornamented;

FIG. 2 is an opposite side view thereof;

FIG. 3 is a rear view; and,

FIG. 4 is a top view.

The bottom is plain and unornamented so its depiction is omitted from the drawings pursuant to MPEP 1503.02.
